UNITED STATES PATENT OFFICE.

JOHN W. KING, OF NEW YORK, N. Y., ASSIGNOR TO KING MECHANISM & ENGINEERING COMPANY, A CORPORATION OF NEW YORK.

DUMPING-RECEPTACLE.

1,043,845.

Specification of Letters Patent.

Patented Nov. 12, 1912.

Application filed December 21, 1909. Serial No. 534,254.

To all whom it may concern:

Be it known that I, JOHN W. KING, a citizen of the United States of America, and a resident of the borough of Bronx, in 5 the city of New York, county of New York, and State of New York, have invented certain new and useful Improvements in Dumping-Receptacles, of which the following is a specification.

10 My invention relates to improvements in receptacles which may or may not be mounted on vehicle wheels and constitute permanent vehicle bodies. However, the particular application is to dumping-cars of the 15 class in which the gate is unfolded downward to discharge the burden when the body is tilted, and in which the gate is restored to its normal position when the body is righted after discharging its contents.

20 It has for its object the provision of means for effecting automatically the unfolding of the gate, to form an apron for the further discharge of the burden, and for effecting automatically and positively 25 the closing of the gate and locking it securely in position by the operation of restoring the receptacle to its normal position.

A further object is to make the means provided of a character embodying advantages in point of operation, simplicity and inexpensiveness.

30 A further object is to make a suitably formed cam a part of the mechanism for controlling the unfolding and folding of the 35 gate whereby the constructor is free to give it such shape as will cause the gate to move relatively to the movement of the body according to any desired law.

These objects I accomplish by hinging or 40 pivoting the gate at or near the plane of the floor, automatically unfolding the same as the car is inclined to dump until it attains a position in preferably, though not necessarily, the same plane but adjacent to the 45 floor of the car, and forms thereby an extended apron or continuation of the said floor over which the load must pass. I thus deliver the load farther from the center of the track, eliminate the possibility of jamming or skimming and consequent hindrance 50 to the discharging burden in the act of dumping as is the case where a gate is raised and the load dumped between the car and the gate, and provide for the discharge of 55 larger fragments of rock than in the last

named case without liability of accident or delay. Upon restoring the body to its normal position, the gate is automatically and positively returned and locked in its position and the construction is so formed that the body is at the same time locked from a horizontal displacement.

In the art of removing material and of grading, dumping vehicles of various types have been employed, for example, some 65 dumping from one end only, or from either end or from both ends; others from one side only, or from either side or from both sides: and various means have been employed for 70 tilting them, for example, air, steam, or simply by hand. But the particular type of vehicle or manner of tilting is not a part of this invention, which is designed to have general applicability to all dumping devices.

75 For purposes of illustration only, the gate and its attending mechanism have been shown attached to a railway car dumping from either side and tilted by hand, as being the most common form of its application, but it is not my desire to be in any way limited to this particular type or manner of tilting.

80 In the accompanying two sheets of drawings, which form a part of this application— 85 Figure 1 is a side elevation showing a receptacle in its normal position constructed in accordance with my invention, and forming the body of a dump-car. Fig. 2 is an end view of the same. Fig. 3 is an end view of 90 the same showing in full lines the receptacle inclined for dumping, and in dotted lines the position of the receptacle partly inclined.

95 An underframe *a* of the car supports a moving body *b* which contains the burden and is inclined to dump and discharge the contents. This body is surmounted upon the underframe *a* and supported thereon by any of the various forms of hinge devices *c* and 100 secured in place by any of the various means that are now employed, one of which consisting of chains *m* being shown.

105 The gates which are hinged at their lower edge to the floor are attached at their ends to downwardly extending levers *e* *e'* respectively, which are also hinged coincidentally at the lower edge of the gates in the plane of the floor by the pivot points *f* *f'* respectively, about which the gates *d* *d'* spec- 110

tively turn, the upper end of the levers being held in a vertical position by the thrust blocks h h' respectively.

When the body of the car is tilted for dumping on the side illustrated in Fig. 1, the levers e e' are allowed to slide around the thrust blocks h h' respectively, the relative position of said levers depending on the inclination of the car body b and the movement of the pivot point around said thrust blocks. A relative movement of the gate in a downwardly and outwardly direction is thus secured, until the body reaches its maximum inclination, at which point the lower ends of the levers e have passed around the outer edge of the thrust blocks h and rest on its under side, and the levers e lie parallel to the plane of the floor, while the gate d secured to the opposite ends of the levers e lie parallel to and in the same plane as the car-floor providing a continuation or an extension thereof. On the opposite and elevated side of the body b the gate d' secured similarly to levers e' pivoted in like manner at f' disengages from thrust blocks h' as the body is inclined to dump and remains in its normal position relative to the floor of the car and is held in this position by the action of gravity. When restoring the body to its normal upright position the levers e' descend from the elevated position until they come in contact with upper and outer surfaces of the thrust blocks h' , upon which they slide until the body reaches its normal upright position, coincident with locking of the gate d' .

The closing of the gate d is accomplished in a manner that is positive throughout its operation and in a direct relation with the movement of the body, in which the inwardly extending portions of the arms e resting against the underside of the stationary thrust blocks or cams h slide outwardly and upwardly as the body is raised, acting upon the fulcrum pivots f and forcing the gate to acquire a corresponding upwardly and inwardly movement until the body reaches its normal upright position where the thrust blocks h and h' maintaining the downwardly projecting portions of gate levers e and e' in their respective extended position close their respective gates d and d' and lock the car body against a horizontal or lateral displacement in either direction.

While I have only described the operation of my construction when the body is tilted for dumping on the side illustrated in Fig. 1, it is obvious that corresponding parts would operate in like manner when the body is tilted for dumping on the opposite side, or on the end if the body were mounted for the last named purpose.

What I claim as new, and desire to secure by Letters Patent of the United States, is—

1. A receptacle comprising a body por-

tion capable of being tilted to dump in either direction and having oppositely disposed gates either of which is adapted to open downward contemporaneously with the tilting of the body, the opening movement being controlled thereby, and the opened gate being positively closed by restoring the body to its normal position, substantially as described.

2. A receptacle comprising a body portion capable of being tilted to dump in either direction and having positively disposed gates either of which is adapted to open downward contemporaneously with the tilting of the body, and forming an apron for the further discharge of the burden carried by the body, the opening movement being controlled by the tilting of the body, and the opened gate being positively closed by restoring the body to its normal position, substantially as described.

3. The combination of a receptacle comprising a body capable of being tilted for dumping in either direction, oppositely disposed gates, either of which is automatically released and allowed to open downward when the body is tilted for dumping, and rigid means for positively closing the opened gate when the body is restored to its normal position, substantially as described.

4. The combination of a receptacle comprising a body capable of being tilted for dumping in either direction, oppositely disposed gates either of which is automatically released and arranged to open downward to form an apron for the further discharge of the load carried by the body when the body is tilted for dumping, and means for positively closing the open gate actuated by the return of the body to its normal position, substantially as described.

5. In a dumping device the combination of a receptacle comprising a body, a gate pivoted on the body arranged to open with the tilting of the body, a cam for controlling the opening movement of the gate, and for positively closing the gate, substantially as described.

6. The combination of a receptacle comprising a body, a gate pivoted thereto, a cam, and a lever attached to the gate co-operating with the cam to positively close the gate upward as the body is restored to its upright position after being tilted for dumping, substantially as described.

7. The combination of a receptacle comprising a body capable of being tilted to dump in either direction, oppositely disposed gates pivoted thereto, either of which is adapted to open downward, cams, and levers attached to the gate co-operating with the cams to positively close the opened gate as the body is restored to its upright position after being tilted, substantially as described.

8. The combination of a receptacle comprising a body, a gate pivoted thereto, levers attached to the gate and means by which the levers are controlled to close the gate and lock the body against lateral displacement, substantially as described.

9. The combination of a receptacle comprising a body capable of being tilted for dumping, a gate pivoted thereto, levers attached to the gate having downwardly extending ends and cams which positively control said levers to limit the opening of the gate while the body is tilted and close and lock the gate and lock the body against lateral displacement when the body is righted, substantially as described.

10. The combination of a receptacle comprising a body, a gate carried thereby during the movement of the body, a lever at-

tached to the gate and a cam about which 20 the end of the lever is guided by the dumping of the body, substantially as described.

11. In a dumping device, the combination of a receptacle mounted to move for dumping, a gate carried thereby during the movement of the body, a lever controlling the position of the gate, and a bearing body fixed in relation to the dumping movement of the receptacle, the lever having a sliding movement on the bearing body to control 30 the opening and closing of the gate.

Signed at New York, N. Y., this 17th day of December, 1909.

JOHN W. KING.
